Primary Examiner — Paula Greene(74) *Attorney, Agent, or Firm* — McGinn IP Law Group, PLLC(57) **CLAIM**

The ornamental design for optical module, as shown and described.

DESCRIPTION

FIG. 1 is a front, top and left side perspective view of an optical module showing our new design;

FIG. 2 is a front, bottom, and right side perspective view thereof;

FIG. 3 is a front, bottom, and left side perspective view thereof;

FIG. 4 is a front, top, and right side perspective view thereof;

FIG. 5 is a front view thereof;

FIG. 6 is a top view thereof;

FIG. 7 is a bottom view thereof;

FIG. 8 is a cross sectional view thereof taken along line VIII-VIII of FIG. 6;

FIG. 9 is a right side view thereof; and,

FIG. 10 is a left side view thereof.

The broken lines form no part of the claimed design.
